CLAIM

The ornamental design for a record display bin, substantially as shown and described.

DESCRIPTION

FIG. 1 is a perspective view of a record display bin according to my new design;

FIG. 2 is a top plan view thereof;

FIG. 3 is a front elevational view thereof;

FIG. 4 is a side elevational view thereof;

The rear of the article is unornamented and follows the contours of the interior.

FIG. 1

FIG. 2

FIG. 3

FIG. 4
